CARRY BAG

Albin J. Mengis, Philadelphia, Pa., assignor to Wolf Brothers, Inc., Philadelphia, Pa., a corporation of Pennsylvania

Application December 29, 1953, Serial No. 400,920

1 Claim. (Cl. 229—54)

This invention relates to an improvement in the type of bag generally known as a carry bag and, more particularly, to an improved relation between the finger openings and the locking flap of a carry bag.

In carry bags of the type disclosed herein in which a tongue is folded through finger openings in the bag panels, there occasionally occurs in the manufacture of a bag an incomplete cutting of the cut lines forming the locking tongue in the bag closing flap. When this occurs the user of the bag experiences considerable difficulty in folding the tongue through the finger openings inasmuch as the folding cannot be accomplished until the incompletely cut material has been separated by tearing.

It is an object of this invention to so arrange the relative positions of the edge of the finger opening and the cut line forming the tongue in the closing flap that, as the user of the bag forces the tongue through the finger opening, the cut line forming the tongue in the flap passes over or is coincident with, for at least an initial portion of its length, the edge of the finger opening and thus, as the tongue is forced through the finger opening, a shearing action will take place over the edge of the finger opening which will serve to part any remaining strands of material which may exist as a result of incomplete cutting of the tongue forming cut line when the bag was manufactured.

This desirable improvement is accomplished without incurring an acute angle at either corner of the edge of the flap or the tongue adjacent to the cut line and the disadvantages which would result therefrom.

It is a further object of the invention to provide the foregoing advantageous bag form without necessitating the removal of a chip or other form of surplus paper which is highly undesirable and produces complications in the manufacturing process.

Having now indicated in a general way the nature and purpose of this invention, I will proceed with a detailed description of a preferred embodiment thereof with reference to the accompanying drawings in which:

Figure 1 is a plan view of one side of the paper bag embodying the invention with the bag closing flap in an open position;

Figure 2 is a plan view of the bag shown in Figure 1 with the bag closing flap folded downwardly; and

Figure 3 is a plan view of the bag shown in Figure 1 with the closing flap folded downwardly and the tongue folded through the finger opening and turned upwardly, the bag being formed in a condition for carrying.

Referring to the drawings, the bag includes a front panel 2 and a rear panel 4. In the embodiment shown, the front and rear panels join at the bottom of the bag and are joined together by means of a pasted flap 6 at the sides of the bag. As will be hereinafter evident, however, any type of bag construction may be employed in conjunction with the present invention so long as front and rear bag panels are involved.

A reinforcing patch 8 is attached to the inside of the upper portion of the front panel 2 and a reinforcing

2

patch 10 is attached to the inside of the rear panel 4. Aligning finger openings 12 are cut through the front and rear panels and their reinforcing patches. An extension 14 of the rear panel 4 provides a closing flap.

5 The reinforcing patch 10 has an extended portion 16 which is applied to the closing flap 14.

The upper and lower edges of the finger openings are formed by outwardly bowed generally horizontally extending cut lines 18 and 20. While these lines are shown as bowed, they may, if desired, be substantially parallel. The sides of the finger openings are formed by cut lines 22 and 24 which are in converging relation in the direction of the upper end of the bag and which form angles of approximately 20° with the longitudinal axis of the bag. 15 The lines 18 and 20 each join the lines 22 and 24 through radiused corners which are so formed in order to avoid the occurrence of stress concentrations which would otherwise exist if the corners were sharp or square.

A locking tongue 26 is formed in the flap by a pair 20 of spaced cut lines therein. Each of the cut lines extends perpendicular to the edge of the flap as indicated at 28 in the region of the edge of the flap. The cut lines thereafter each diverge as indicated at 30 as they 25 extend into the flap. The cut lines then terminate in inwardly turned arcuate portions 32 which form ears 34 at the inward portions of each side of the tongue.

A fold line 15 separates the flap 14 from the panel 4 of the bag. The flap 14 is of such a length that, when the flap is folded over the open end of the bag, the edge 30 37 of the flap extends transversely of the finger openings 12 coincident with the widest portion thereof as indicated generally by the numerals 38. The portions 28 of the cut line forming the tongue 26 are spaced apart by a distance slightly greater than the maximum width of 35 the finger opening. This spacing provides a small dimension between the finger opening and the cut line 28 as indicated at 36. This dimension is only sufficient to provide a production tolerance, which may be of the order of a sixteenth of an inch, to prevent any possibility 40 that the portion 28 of the cut line forming the tongue will overlap the finger openings 12 and permit the edge 37 of the flap 14 adjacent to one of the cut lines 28 from extending in overlapping relation with the finger openings 12. Such an overlapping relation would be 45 highly undesirable for appearance reasons and in view of the possibility of the edge of the paper cutting the fingers of the person carrying the bag and having his fingers passing through the finger openings 12.

As shown in Figure 3, after the closing flap 14 has 50 been folded over the bag and the tongue 26 folded through the finger openings 12, the ears 34 will engage the outer surface of the back panel 4 and serve to retain the tongue in a folded up position. The upwardly converging formation of the finger openings and the inwardly diverging formation of the cut lines 30 provide 55 large areas of overlap between the ears 34 and the rear panel 4 of the bag insuring secure locking of the bag handle in a folded or carry condition.

When the tongue 26 is being folded from the position 60 shown in Figure 2 to the position shown in Figure 3, it will, of course, separate from its adjacent relation with the flap 14. Due to the substantially overlapping relation of the cut line 28 and the adjacent edges 22 and 24 of the finger openings, this parting occurs for the initial 65 separation of the tongue from the adjacent portion of the flap 14 to the region of the cut line 28 in such a manner that, if in the process of bag manufacture the cut lines were not completely cut through the material forming the bag panel and the reinforcing patches thereon, a shearing action will occur over the edges 22 and 24 of 70 the finger opening 12.

As the parting progresses along the cut line from the

region 30 thereof, any portion of the cut line which is not completely cut will be drawn over by the flexibility of the material forming the flap 14 so that the region of the cut line which has been incompletely cut lies over the edge 22 or 24 of the finger opening. Thus a shearing action will also occur in either of these regions if either cut line has not been completely cut through and the bag material not completely severed when the bag was manufactured.

Incomplete cutting of the arcuate portions 32 is less critical with regard to the folding of the locking flap through the finger openings for the reason that the direction of forces which exist in the flap while it is being folded through the finger openings are such as to act progressively along any remaining uncut material in the cut lines 32 and thus tearing of any remaining uncut material in this portion of the cut line will occur much more readily than it would occur in the region 28 or in the region 30 of the cut line. Thus the shearing action which is so desirably provided in the region 28 of the cut line and is also desirably provided in the region 30 of the cut line is not so necessarily provided in the regions 32 of the cut line.

From the foregoing it will be evident that a bag construction is provided by the present invention in which a shearing action occurs across the portion of the cut line forming the locking tongue adjacent to the outer edge of the closing flap when the tongue is folded through the finger openings. This desirable condition is provided by a bag structure which has no portion of the flap 14 extending over the finger openings and also has no acute angles in either the flap 14 or the tongue 26 existing after the tongue has been folded through the finger opening. Furthermore, the sides 22 and 24 of the finger opening are placed at such an angle as to provide maximum area of overlap of the locking ears 34 with the bag panel without unduly limiting the space within the finger opening. This advantageous structure is further provided without the necessity of any chip removal during bag production. Thus it will be apparent that the particular relation of the parts described provides an

improved bag structure having various desirable qualities not heretofore recognized.

It will be evident, as previously noted, that bags having variously formed bag panels may incorporate the finger opening and locking flap relations disclosed herein. It will further be evident that various other modifications may be made to the embodiment of the invention disclosed herein without departing from the scope of the invention as set forth in the following claim.

What is claimed is:

A carry bag comprising connected front and back panels separated at their upper ends to form an opening for the bag, aligning apertures in said panels adjacent to but spaced from the open end of the bag, said apertures being of generally elongated form and having rounded corners, a closing flap formed as an extension of one of said panels at the open end of the bag, said flap being of such a length that when the flap is folded over the open end of the bag the edge of the flap will extend transversely of said apertures, and a locking tongue formed in said flap by spaced cut lines therein, said cut lines extending perpendicular to the edge of the flap in the region of the edge of the flap and thereafter diverging as they extend back into the flap and terminating in inwardly turned arcuate ear forming portions, the spacing between the cut lines at the edge of the flap being substantially equal to the width of said apertures in the region of the edge of the flap, whereby, when the tongue is folded through said apertures, progressive shearing action will take place along said cut lines commencing at the edge of the flap which will serve to part any remaining strands of material which may exist as a result of incomplete cutting of the cut lines when the bag was manufactured.
